(57) CLAIM

The ornamental design for a wrist supporting apparatus, as shown and described.

DESCRIPTION

FIG. 1 is a front elevational view of a wrist supporting apparatus showing my new design;

FIG. 2 is a top plan view thereof;

FIG. 3 is a right side elevational view thereof;

FIG. 4 is a bottom plan view thereof;

FIG. 5 is a front elevation view showing the straps at a disengaged position; and,

FIG. 6 is a top plan view showing the wrist supporting apparatus in use. The broken line drawing in FIG. 6 view is for illustrative purpose only and forms no part of the claimed design.
